VALVE TAPPET

Cornelius W. Van Ranst, Detroit, Mich., assignor
to Packard Motor Car Company, Detroit, Mich.,
a corporation of Michigan

Application September 19, 1934, Serial No. 744,614

1 Claim. (Cl. 123—90)

This invention relates to internal combustion engines and more particularly to valve tappets for such engines.

In the ordinary valve tappet construction, a contact member is threaded into the body of the tappet and is held in adjusted position by a lock nut. In adjusting this contact member with relation to the body it is necessary to apply three wrenches, one to the body, one to the lock nut and one to the contact member. The body and contact member are held from turning while the lock nut is loosened, the contact member and the body are then turned relatively to adjust the tappet after which the body and contact member are held from turning while the lock nut is tightened. The proper adjustment of the contact member is therefore rather difficult to effect and requires a considerable amount of labor and time.

One object of the present invention is to improve the construction and mode of operation of adjustable valve tappets for internal combustion engines and to produce an improved tappet construction in which any desired adjustment of the contact member with relation to the body of the tappet may be effected, with the expenditure of a minimum amount of labor and time.

Another object of the invention is to provide a novel valve tappet construction for internal combustion engines in which the contact member may be more quickly and easily adjusted with relation to the body of the tappet than could be done in prior constructions and will be held securely in adjusted position.

Another object of the invention is to provide an improved valve tappet construction for internal combustion engines in which the contact member may be adjusted with relation to the body of the tappet and secured in adjusted position by the application of only two wrenches to the parts of the tappet.

With the above and other objects in view the invention consists in a valve tappet construction embodying the novel and improved features hereinafter described and particularly pointed out in the claim, the advantages of which will be readily understood by those skilled in the art.

The invention will be clearly understood from the accompanying drawing illustrating the invention in its preferred form and the following detailed description of the constructions therein shown.

In the drawing, Fig. 1 is a view partly in vertical section and partly in front elevation illustrating a portion of an internal combustion en-

gine provided with a valve mechanism embodying the invention;

Fig. 2 is a detail sectional view taken in a plane containing the axis of the valve tappet and illustrating certain of the parts of the tappet during the process of manufacture, and

Fig. 3 is a detail sectional view taken in substantially the same plane as Fig. 2, and illustrating the parts of the tappet shown in Fig. 2 at another stage in the process of manufacture.

The invention is illustrated in this application as applied to a valve of an internal combustion engine indicated as a whole at 2 and comprises a cylinder 4, a piston 6 operating within the said cylinder, a valve 8 secured to the upper end of a valve stem 10 mounted for longitudinal reciprocating movement in a guide 12 formed on the engine block. The valve stem is moved in one direction in the guide 12 by means of a coiled spring 14 surrounding the valve stem and interposed between a washer 16 engaging the engine block and a retainer disk 18 held against longitudinal movement on the valve stem.

The valve tappet comprises a tappet body 20 mounted for axial reciprocating movement in a guide or bearing 22 formed on the engine block. The lower end of the tappet body is engaged by a cam 24 mounted on a cam shaft 25. The tappet also comprises a contact member 26 mounted on the upper end of the tappet body for engagement with the lower end of the valve stem 10. In order that this contact member may be adjusted axially with relation to the tappet body 20, the contact member is threaded into said body. The contact member 26 is held or locked in adjusted position by means of an annular locking disk 28 threaded on the lower end of the contact member.

This locking disk is made of spring metal and normally has substantially the concavo convex or cupped disk shape in cross section shown in Fig. 2. The body of the tappet is made in two parts as indicated respectively at 20a and 20b, these parts being secured together preferably by welding as indicated at 30 in Fig. 1. The part 20a is formed with an end wall 32 having a central opening 33. In threading the cupped disk 28 and the body of the tappet, before the parts 20a and 20b of the tappet are assembled and secured together, the cupped disk is inserted in the part 20a in contact with the end wall 32 thereof as shown in Fig. 2 and the disk is flattened against said wall by any suitable means. As shown in Fig. 3 the disk is flattened against the end wall of the part 20a of the body of the tappet by means of a hollow cylindrical tool 34 inserted in the part 20a.

28a and engaging the cupped disk. While the disk is in this position, a tap 36 is inserted in the tool 34 and is passed through the openings in the cupped disk and in the end wall 32 of the part 28a of the tappet to thread these parts for the reception of the contact member 26.

After the part 28a and the locking disk have been thus threaded, the contact member 26 may be assembled with the part 28a of the tappet 10 by removing the tap and screwing the contact member into said part and into the locking disk 28 while said disk is held flattened against the end wall 32. The tool 34 is then removed and the parts 28a and 28b are assembled and welded 15 together.

With the above construction, the contact member and the tappet body may be quickly adjusted relatively by applying a wrench to each of these parts and turning relatively the said parts. The 20 contact member will be securely held in adjusted position after each adjustment by the resilience of the locking disk which tends constantly to move the contact member axially with relation to the body 28 of the tappet.

25 In the operation of the valve operating mechanism the forces exerted on the contact member which are produced by the reaction of the valve stem on the same during the upward movement of the valve under the action of the cam 24, and 30 during the downward movement of the valve under the action of the spring 14 tend to force said member downwardly with relation to the body 28 of the tappet. The resilience of the cupped disk 28 also tends to force said contact 35 member downwardly with relation to the body 28 and to press the threads of the contact member against the threads on the tappet body and also to press the threads of the locking disk against said contact member. The frictional contact between the threads of the contact member and respectively the threads of the body of the tappet and the threads of the locking disk prevents the turning of the contact member with relation to said body.

In the above construction the forces exerted on the tappet body 28 and the contact member 26 during the operation of the valve operating mechanism tend to move relatively the said members axially in the same direction as the 5 force exerted by the locking disk 28 tends to move relatively said members. The valve operating mechanism therefor has no tendency to overcome the force exerted by the locking disk and it is necessary to construct said disk so that, when 10 compressed, it exerts only a relatively light force axially on the contact member and tappet body.

It is to be understood that the invention is not limited to the particular construction and arrangement of parts of the illustrated embodiment of the invention, but that the construction shown and described is merely illustrative of the invention and that the invention may be embodied in other forms within the scope of the 15 claim.

Having explained the nature and object of the invention and having specifically described a construction embodying the invention in its preferred form, what is claimed is:

20 In a tappet for internal combustion engines, the combination of a body portion having an apertured end wall, said end wall being threaded at the aperture, a spring metal disk arranged against the inner face of said end wall, said disk in its normal state being cup-shaped, and said 25 disk having an aperture with threads in the aperture so formed that when the disk is in a flat state the threads correspond exactly with the threads in the aperture of said end wall, said 30 spring metal disk being in a flat state with its normally concave face against the inner face of said end wall, and a threaded adjustment member 35 extending through the apertures of said end wall and said disk and in intimate threaded contact with both, whereby the adjustment member 40 retains said disk in its flat state and the disk acts to frictionally lock the adjusting member in adjusted position.

CORNELIUS W. VAN RANST.
